CLAIM

The ornamental design for a motor wire connector housing, as shown and described.

DESCRIPTION

FIG. 1 is a front elevation view of a motor wire connector housing showing the new design in environmental use;

FIG. 2 is a rear elevation view thereof;

FIG. 3 is a first perspective view of a motor wire connector housing;

FIG. 4 is a second perspective view thereof;

FIG. 5 is a front elevation view thereof;

FIG. 6 is a side elevation view thereof;

FIG. 7 is a rear elevation view thereof;

FIG. 8 is a top plan view thereof; and,

FIG. 9 is a bottom plan view thereof.

The broken lines shown represent environmental subject matter and form no part of the claimed design.
